UNITED STATES PATENT OFFICE.

ALBERT ZABRISKIE, OF PATERSON, NEW JERSEY.

FIBER-PREPARED MACHINE.

No. 900,251.

Specification of Letters Patent.

Patented Oct. 6, 1908.

Application filed July 23, 1907. Serial No. 385,121.

To all whom it may concern:

Be it known that I, ALBERT ZABRISKIE, a citizen of the United States, residing at Paterson, New Jersey, have invented certain new and useful Improvements in Fiber-Preparing Machines, of which the following is a specification.

This invention relates to fiber preparing machines, and particularly to that class of such machines as are provided for removing the pulpy portions of the leaves of such relatively coarse growth as sisal, agave and the like, whereby the fibers of said leaves are made available for commercial purposes.

In the drawings accompanying this specification, I have illustrated one form of a fiber preparing machine embodying my improvements. Therein Figure 1 is a general plan view. Fig. 2 is an end elevation looking from the feeding end of the machine and with portions of the feed mechanism removed. Fig. 3 is a side elevation looking in the direction of arrow 8 of Fig. 1 and with those parts in front of line 1, 1 removed. Fig. 4 is an enlarged view of a detail of the scutching mechanism. Figs. 5 and 6 are step views showing the operation of a detail of my improvements. Fig. 7 is a view of a leaf partly cleaned.

The general type of machine to which I have illustrated my improvements applied comprises two scutching wheels 10, 11 located one after the other in the horizontal plane and having their axes parallel but offset so that the peripheries of said wheels overlap when viewed axially; a pair of conveyer chains 20, 22 for serving the first scutching wheel 10 and a second pair of conveyer chains 21, 23, offset horizontally from the first pair of chains, for taking the partly cleaned leaves from said first pair of chains and presenting the same to the action of the second scutching wheel 11.

The object of my improvements is to furnish a machine of the general class specified, simple in construction and which may be operated with a relatively small expenditure of power and with a minimum waste of the fiber of the leaf. With these objects in view I fix the first scutching wheel 10 on a suitable shaft 12 and which shaft has its bearings at 14, 16 in frames 2, 3 respectively. Said shaft 12 is provided with a pulley 6 to which power may be supplied by means of a belt not shown, directly from any suitable source of power. The second scutching wheel 11 is

fixed on shaft 13 mounted in bearings 15, 17, 19 in frames 3, 4 and rail 5 respectively. Said frames 2, 3, 4 are fixed to and are standing from bed plate 9 of the machine, while rail 5 extends horizontally from frame 2 to frame 3 and is fixed thereto. Said shaft 13 is provided with a pulley 7 to which power may be supplied by means of a belt from any convenient source of power such as that from which scutching wheel 10 is driven. Said scutching wheels 10, 11 are provided with beating blades 100, 110 suitable for coaction with concave plates or shoes 30, 31 all respectively. As said shoes 30, 31 are duplicates, a description of one will suffice for both. Shoe 30 has the contour of its working face throughout the major part of its length substantially concentric with the periphery of its scutching wheel 10, but the upper part of the face of said shoe is of peculiar and novel contour.

Heretofore, according to the best practice in this art, there often has been a distinct line of demarkation of the beginning of engagement of the scutching blade and shoe whereby the action of removing the pulp of the leaf has been so abrupt and harsh as to cause a material and wasteful loss of fiber by breakage at said line of beginning of coaction of scutching blade and shoe. Also said distinct line of demarkation between cleaned and uncleared leaf is a fruitful source of waste at the second scutching wheel as that wheel is thereby required to commence its work abruptly thus causing injury to the fiber. In my improved machine I have eliminated these objectionable features by connecting the top edge 108 of shoe 30, said edge being relatively remote from the path of scutching blades 100, with the concentric portion 109 of said shoe by a plane or curved surface 300 preferably tangent to said concentric portion 109 where it merges therewith. I thereby obtain a graduated opening 105 as 105 between the face of the shoe 30 and the path of the operative edge of the scutching blade. Also I have so located the conveyer chains relative to the top edge of the scutching shoe (Fig. 4) as to maintain the leaf free from contact with the upper face as 108 of said shoe. By this means I eliminate any danger of breaking the leaf against the top edge of the shoe and the leaf is reduced gradually and a zone of transition from unbeaten leaf to clean fiber is provided. The integrity of the fiber is thereby conserved and loss by

- breakage under the action of the first scutching wheel reduced to a minimum. Furthermore by the formation in the leaf of this zone of transition said leaf is thereby prepared for 5 gradual and relatively less drastic treatment by the second scutching wheel. This relatively gentle treatment by the second wheel is particularly desirable as the holding of the leaf by chains 21, 23 is by the cleaned and 10 therefore relatively weaker portions only of said leaf, so as to present all of the remaining uncleared portions to be operated upon by the second wheel. In my improved machine the heretofore great wastefulness in the sec- 15 ond scutching operation has been reduced to a minimum and substantially all the fiber of the leaf conserved for useful disposal.
- For adjusting the scutching shoes 30, 31 relative to their respective wheels 10, 11, I 20 provide the usual horizontal adjustment by means of a screw as 101 for shoe 30. Heretofore, as far as I am aware, the scutching shoes in machines of the class herein specified, have been provided with said horizontal 25 adjustment only, whereby it was impossible to obtain desired gradations of action on those portions of the leaf remote from the conveyer chains and more or less directly under the scutching wheel. To remedy this 30 deficiency I have provided a vertical adjustment by means of a wedge as 102 for said shoe 30. Said wedge may be moved in the horizontal plane to raise or lower said shoe by means of adjusting screw 103.
- 35 In the prior art machines of the general class herein specified have been more or less inefficient because of the springing of the upper part of the scutching shoe under the severe action of the scutching wheel. A 40 further feature of my improvements comprises means for counteracting said tendency of the scutching shoe to spring out of place. To this end I have provided a resistance post as 104 extending from the upper part of said 45 shoe as 30 to a rigid part of the frame-work as rail 5. It will be observed that the bearings of the scutching wheel 10 are fixed to the same general rigid frame-work as that against which post 104 abuts, whereby irre- 50 spective of whatever general vibration may occur in running the machine said scutching wheel and its coacting shoe will maintain their relative and predetermined operative positions to each other. To provide for the 55 hereinbefore described adjustment of shoe 30 I have threaded post 104 where it passes through a vertically elongated hole in rail 5 and provided lock-nuts 106, 107 thereon for engagement with said rail 5.
- 60 The several conveyer chains 20, 21, 22, 23 are made up of individual links as link 82 of chain 20 pinned together and said links preferably have their gripping faces corrugated lengthwise as at 83 Fig. 4. Said cor- 65 rugations are preferably so arranged cross-

wise the link that opposing links will have their corrugations mesh, Fig. 4, thus affording superior gripping ability. The two pairs of conveyer chains 20, 22 and 21, 23 respectively are mounted and actuated as follows: I will first describe the mounting and actuating of upper chains 20, 21. Supported by the upper spans of frames 2, 3, 4 and depending therefrom are stringers 40, 50 running lengthwise the machine. From 70 near the rearward end of stringer 40 depends bearing 41. Between the bifurcated ends thereof, on shaft 43 is fixed sprocket 42 for the support of the rearward portion of conveyer chain 20. From the forward end of 75 stringer 40 depends bearing 42 and from the rearward end of stringer 50 depends bearing 52. In these bearings is mounted shaft 53 on which is fast sprocket 54 for the support of the forward portion of chain 20 and sprocket 85 56 for the support of the rearward portion of chain 21. The forward portion of chain 21 is supported on sprocket 58 fixed on shaft 57 mounted in the bifurcated ends of bearing 55 depending from the forward end of 90 stringer 50. Power is communicated to shaft 53 carrying sprockets 54, 56 and thence to chains 20, 21 by the following means. Said shaft 53 has its outboard end supported in bearing 59 on rail 5, and inboard, adja- 95 cent to said bearing, has worm-gear 60 fixed thereon. Said worm-gear meshes with and is driven by worm 61 fixed on shaft 13 of scutching wheel 11.

Lower chains 22, 23 are mounted and 100 driven as follows: In bearing 27 on bracket 28 extending rearwardly from frame 2 is supported one end of shaft 26; the other end of said shaft is supported in the upper end of bracket 29 upstanding from bed plate 105 9. On said shaft 26 and adjacent to bracket 29 is fixed sprocket 62 for supporting the rearward portion of chain 22. In suitable bearings in the bifurcated upper end of bracket 64 is mounted shaft 65, on the out- 110 board ends of which are fixed sprockets 66, 67 respectively. Sprocket 66 is provided for supporting the forward portion of chain 22 and sprocket 67 is provided for supporting the rearward portion of chain 23. The 115 forward portion of said chain 23 is supported on sprocket 68 fixed to shaft 69 mounted in the bifurcated upper end of bracket 70 up- 120 standing from bed plate 9. For supporting the upper run of chain 22 a table 71 mounted 125 on legs 72, 73 upstanding from bed plate 9 is provided.

To minimize friction between the chain and table a series of anti-friction rolls, 74, 74 is provided pivoted on said table. The up- 125 per run of chain 23 is similarly supported by table 75 on legs 76, 77 and said table is pro- vided with anti-friction rolls 78, 78.

To reduce the friction and minimize the power required for driving my improved 130

machine, I have omitted all special gearing or belts for driving the lower chains 22, 23 and supply power thereto only through frictional contact with their coacting upper chains respectively. My machine is thereby also simplified in construction and reduced in weight over the prior art. The lower run of chain 20 is urged to engagement with the upper run of chain 22 to be driven thereby to grip the leaves or material to be operated on by scutching wheel 10, by means of a series of rolls 79, 79. Said rolls are mounted in the lower ends of vertically guided plungers 80, 80 respectively, carried in frame 81 depending from stringer 40. Said rolls are urged downwardly by means of springs 82, 82. Said frame 81 is of such contour as to allow free passage for the upper run of chain 20. The lower run of chain 21 is urged to engagement with the upper run of chain 23 by means similar to those just described in connection with chain 20 and detailed description thereof is deemed unnecessary.

For delivering the leaves or other material to be treated into the bite of conveyer chains 20, 22 an endless traveling apron, in the present instance comprising two sections 18, 180, is provided. This apron is mounted at its forward end upon pulleys 24, 25 fixed on either side respectively, of sprocket 62 on shaft 26, and which shaft is the source of power for said apron. The rearward end of apron 18, 180 is carried by pulley 32 on shaft 33. Said shaft is supported in bearings 34, 35 projecting from table 36 on bracket 37 upstanding from bed plate 9. To assist said feed apron 18, 180 to deliver the leaves into the bite of chains 20, 21, I provide two pressure belts 84, 85 above said apron. The operative runs of these belts travel in the same direction and at the same speed as the upper run of said apron and are efficient to hold the leaves in place on said apron and prevent their disarrangement as they are delivered into the grip of the conveyer chains. Said belts 84, 85 have their forward portions supported on and are driven by pulleys 86, 87 respectively fast on shaft 43 of sprocket 42. The rearward portions of said belts are supported by pulleys 88, 89 respectively pivotally mounted on shaft 90 in bracket 91 rearwardly reaching from stringer 40.

Looking from the feeding end of the machine, directly forward of scutching wheel 10 and directly rearward of conveyer chain 23, is provided means for assisting those portions of the leaves that have been cleaned by said scutching wheel 10 into the bite of conveyer chains 21, 23 preparatory to the treatment of their uncleared portions by scutching wheel 11. This means comprises an endless traveling belt 95 mounted obliquely lengthwise the machine and so arranged as to underlie the hanging fibers close to or near conveyer chains 20, 22 and as said fibers

travel thereon draw them out horizontally. With this end in view I have mounted in bracket 92 on table 71 pulley 93 for supporting the inboard end of said belt 95; and in bracket 94 upstanding from bed plate 9, on shaft 96, I have fixed pulley 97 for supporting the forward and outboard portion of said belt 95. Power may be communicated to pulley 97 and shaft 96 from shaft 53 by means of a universal joint connecting the adjacent ends of said shafts. For assisting said cleaned portions of the fiber onto traveling belt 95, I provide a guide rod 112 projecting forwardly from table 71 and extending a short distance parallel and level with the upper run of said belt 95. As the cleaned portions of the fiber are carried forward by belt 95 there is a tendency for the unsupported portions of said fiber between conveyer belts 20, 22 and belt 95 to sag from the horizontal, Fig. 5. To counteract this tendency and insure an accurate delivery into the bite of conveyer chains 21, 23 I have provided a wheel 99 fixed on shaft 65 between sprockets 66 and 67 for revolution therewith. Said wheel preferably has a narrow face and of such a diameter that its apex is above the plane of the upper face of conveyer chain 23 so that as the cleaned ends of the leaf pass thereover they will be insured passage onto said chain, Fig. 6. The periphery of said wheel 99 is illustrated as concentric and smooth but it may be roughened or provided with teeth if desired.

The operation of my improved machine is as follows: Power being applied to pulleys 6, 7 and through shaft 13 to the conveyer belts and their appurtenant feeding means, the machine is started. Leaves of sisal or other materials to be treated are placed on feed apron 18, 180 and preferably approximately at right angles to the line of travel thereof as at 120 Fig. 1. The forward movement of said apron carries the leaves under the lower runs of belts 84, 85 respectively, and thus held said leaves are delivered about midway their length into the grip of conveyer chains 20, 22. By means of the corrugated faces of the links of said chains and under the pressure of spring impelled rolls 79, 79 said leaves are tightly gripped and are carried forward and their right-hand portions delivered onto shoe 30 to be operated upon by blades 100 of scutching wheel 10, Fig. 4. The gradually upwardly receding face 300 of the entrance end of said shoe prevents abrupt or unduly harsh action of the scutching blades on the leaf and removes the pulp from the leaf in a downwardly increasing degree until under the coaction of said blades 100 with the concentric portion 109 of the face of shoe 30 substantially clean fiber only remains. Said leaf with its right-hand portions thus cleaned is now carried onward off from shoe 30 and out of the sphere of action of scutching wheel 130

10 thereon. The cleaned portions of said leaf hanging outwardly and downwardly from between conveyer chains 20, 22 now ride over guide rod 112 and onto the inward 5 end of the upper run of belt 95, Fig. 6. As that upper run recedes from said chains the cleaned portions of the leaf are more or less straightened out horizontally and led to lifting wheel 99. By this wheel said cleaned 10 portions of the leaf are lifted and delivered accurately into the grip of the second pair of conveyer chains 21, 23, Fig. 6, and presently pass out of engagement with chains 20, 21. This leaves all the uncleaned portion of the 15 leaf extending outwardly to the left of conveyer chains 21, 23 and convenient to be operated on by scutching wheel 11 in coaction with shoe 31. Continuing its progress said leaf forthwith passes onto the face of shoe 31 20 and under the action of scutching wheel 11. The already described zone of transition from uncleaned to cleaned portions enables the leaf to offer a minimum resistance to the action of the second scutching wheel whereby 25 the integrity of the fiber is conserved and the remaining pulpy portions of the leaf removed with relatively small waste of fiber. The now completely cleaned leaf of which only the fiber remains now passes out from under 30 scutching wheel 11 and off shoe 31 and is discharged from the diverging ends of conveyer chains 21, 23 into some suitable receptacle not shown.

I claim:

35 1. The combination of a scutching wheel and a scutching shoe, said shoe having the major portion of its working face substantially concentric with and relatively near the path of the scutching wheel and having its 40 top edge relatively remote from said path of the scutching wheel and having said top edge connected with the concentric portion of said face by a surface tangent to said concentric portion where it merges therewith, means for 45 adjusting the scutching shoe vertically and other means for adjusting the scutching shoe horizontally relative to the scutching wheel.

2. The combination of a scutching wheel and a scutching shoe, means for adjusting the 50 scutching shoe bodily vertically and means

for adjusting the scutching shoe bodily horizontally relative to the scutching wheel.

3. In a fiber preparing machine the combination of a set of two conveyer chains having longitudinal grooves in their working faces, 55 said chains being mounted upon rear and forward sprocket wheels respectively, and parallel but offset in different planes and so arranged that the forward sprocket of the first chain is co-axial with the rearward sprocket 60 of the second chain, a second set of two chains similarly mounted and disposed above the first set of chains respectively, said second set of chains having grooves in the working faces thereof complementary to the 65 grooves in the first set of chains for frictional engagement therewith, means for actuating one set of said chains, the other set of said chains being driven by friction from the first set thereof, an obliquely disposed belt between the two chains of the lower set and a wheel between the first and second chains of the lower set and co-axial with the common sprocket axis of said chains to lift the fiber for delivery onto said second chain of the 70 lower set.

4. In a fiber preparing machine the combination of two conveyer chains mounted upon rear and forward sprocket wheels respectively, said chains being parallel but offset in 80 different planes and so arranged that the forward sprocket of the first chain is co-axial with the rearward sprocket of the second chain, an obliquely disposed belt situated adjacent to the first belt and extending beyond 85 the rearward sprocket of the second belt and a wheel disposed between the forward sprocket of the first chain and the rearward sprocket of the second chain and co-axial therewith, to assist the delivery of the fiber 90 from the first chain and the oblique belt onto the second chain.

Signed this twentieth day of July, 1907 at Paterson New Jersey, before two subscribing witnesses.

ALBERT ZABRISKIE.
